UNITED STATES PATENT OFFICE

107,347

DESIGN FOR A DRESS

Abner C. Barnhart, New York, N. Y.

Application October 20, 1937, Serial No. 72,321

Term of patent 3½ years

To all whom it may concern:

Be it known that I, Abner C. Barnhart, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the back opening dress disclosed of the specific collar and cuff members which are trimmed by contrastingly colored strips of material, as shown.

I claim:

The ornamental design for a dress, substantially as shown and described.

ABNER C. BARNHART.
